US0D1001986S

(12) **United States Design Patent** (10) **Patent No.:** **US D1,001,986 S**
(45) **Date of Patent:** **** Oct. 17, 2023**

(54) **HUMIDIFIER**

- (71) Applicant: **Coway Co., Ltd.**,
Choongcheongnam-do (KR)
- (72) Inventors: **Jungjae Jeon**, Seoul (KR); **Eung Kyu Park**, Seoul (KR); **Sumin Shin**, Seoul (KR)
- (73) Assignee: **Coway Co., Ltd.**,
Choongcheongnam-Do (KR)

(**) Term: **15 Years**

(21) Appl. No.: **29/807,687**

(22) Filed: **Sep. 14, 2021**

(30) **Foreign Application Priority Data**

- Mar. 16, 2021 (KR) 30-2021-0012596

(57) **CLAIM**

The ornamental design for a humidifier, as shown and described.

DESCRIPTION

FIG. 1 is a front perspective view of a humidifier showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown throughout the views depict unclaimed portions of the humidifier and form no part of the claimed design.

1 Claim, 7 Drawing Sheets
